UNITED STATES PATENT OFFICE.

DAVID H. DILLMAN, OF FREDERICKSBURG, PENNSYLVANIA.

FIRE-ESCAPE.

SPECIFICATION forming part of Letters Patent No. 341,321, dated May 4, 1886.

Application filed January 19, 1886. Serial No. 189,754. (Model.)

To all whom it may concern:

Be it known that I, DAVID H. DILLMAN, of Fredericksburg, in the county of Lebanon and State of Pennsylvania, have invented a new 5 and useful Improvement in Fire-Escapes, of which the following is a description.

My invention relates to an improvement in the class of endless-ladder fire-escapes adapted for attachment to the cornice or side of a building, contiguous to a window or other place of exit, and to operate automatically when a person steps upon the ladder, so as to convey him to the ground in safety.

The features of novelty are as hereinafter 15 described and claimed.

In accompanying drawings, Figure 1 is a perspective view illustrating my invention applied to a building. Fig. 2 is a side sectional elevation of the same. Fig. 3 is a front view 20 of a portion of the apparatus. Fig. 4 is a detail perspective view of the escapement-anchor.

The endless-chain ladder A is suspended from and travels on sprocket-wheels B, fixed on a horizontal shaft, 1, journaled in a box or 25 casing, C, which is attached to the cornice and side of a building, D, as shown. The ladder A runs at its lower end on similar chain or sprocket wheels, E E, mounted on a shaft journaled in brackets F, affixed to the side of the 30 building at any preferred height above the ground. The aforesaid shaft 1 carries two spur-gears, G G. Within the said box C are journaled two other shafts, 2 and 3, which are parallel to the former, 1. The shaft 2 carries 35 an escape-wheel, H, and two gears, I I, that mesh with gears G G. The third shaft, 3, is affixed to the anchor K, that acts on escape-wheel H. On this same anchor-shaft, 3, is fixed a vibrating frame, L, which is arranged 40 vertically, and serves both as a regulator and alarm—that is to say, when a person steps from a window or other upper exit of the building upon the inner side of the chain ladder A his weight causes it to travel downward on that 45 side, thereby rotating the shafts 1 and 2, together with their attached gears G I and escape-wheel H, in the directions indicated by arrows. The rotation of the escape-wheel thus imparted causes oscillation of the anchor 50 K and corresponding vibration of the aforesaid frame L. The latter is provided near its upper end with a weight, a, whereby it sub-

serves the purposes of an alarm, and also aids the escapement or anchor K in regulating the action of the escape apparatus proper. The 55 part a acts as a hammer-head, which, striking on the bell M at each complete vibration of frame L, sounds an alarm that indicates to all outside the building the operation of the escape, and, second, it loads the frame L so that 60 its oscillation is limited in rapidity to that extent, and thus enables it to regulate the rapidity with which the ladder may travel with the load of persons availing themselves of that means of descent and escape from the building. 65

To indicate to all remaining occupants of the building C the place of exit where the escape is operating, I arrange a bell-alarm, N, 70 Fig. 2, within the same and connect its hammer with an arm, b, of the anchor-shaft 3 by means of a rod, c. Thus the anchor and the weighted regulator vibrate, and both alarms sound simultaneously while the ladder is in use. The latter travels in either direction, 75 which is sometimes advantageous in facilitating descent, and also prevents malicious persons from using it as a means of ascent for gaining access to the upper portions of the building. 80

It will be noted that the escapement is not of the ordinary construction—that is to say, the teeth of wheel H are short, and have both sides of equal length, and the anchor K has pallets adapted to enter between and momentarily lock with the teeth, and also to ride over them, whichever way the said wheel may be rotated. This relative construction of the parts of the escapement is necessary to the before-described operation of the apparatus. 85 90

The special construction of the pallets of the anchor is as follows: The ends d of the latter are curved exteriorly, and have plain or flat inner faces, which are composed of pieces e, hinged to the inner termini of said 95 curved portions, and held normally pressed against studs or stops f by means of spiral springs g, placed between them and the curved end portions, d, and encircling guide-pins attached to the hinged pieces. Thus the latter are arranged transversely or at nearly right angles to the longer axis of the anchor. The curved or rounded portions of the pallets work easily against one side of the teeth of the es- 100

cape-wheel H, and the hinged pieces allow their points to strike and slip off with less noise and jar than would be incident to the use of pallets of ordinary construction. The 5 springs g allow a rebounding action, which favors easy and proper action of the vibrating frame or regulator L.

Another feature of my invention is the means for adjustable attachment of the box D to the 10 building. Cornices vary in form, size, and degree of lateral projection, and hence a uniform or fixed attachment cannot always be employed. I support the box D and its attachments from the cornice by screw-couplings— 15 that is to say, couplings formed of the link-shaped nuts h, and two threaded rods, i i, that are hinged, respectively, to the box and to plates screwed to the cornice. The lower portion of box D is secured to the side of the 20 building by bars k, Fig. 1, which have longitudinal slots provided with angular feet having notches, both of which receive screw-bolts, as shown. By adjustment of said screw-couplings and bars the box D may be attached and 25 supported in proper position for the required operation of the apparatus. The bell M is supported upon a standard, whose curved lower end is slotted lengthwise, to allow the bell to be adjusted relative to the cornice and hammer 30 a, as conditions may require. For the same purpose the hammer a is also made adjustable laterally on a horizontal bar, l, and the said bar is adjustable vertically on frame L. Both the hammer and its supporting-bar are 35 clamped by screws m in any adjustment. The front of box D is hinged to allow access to the works within, but is held normally closed by a hasp and padlock.

What I claim is—

1. In a fire-escape, the combination, with the 40 bell and vibrating frame, of a hammer proper, which is made adjustable to adapt it for operation under different conditions, as set forth.
2. In a fire-escape, the combination, with the 45 bell and vibrating frame, of a hammer-head and an adjusting device which adapts the latter for being shifted vertically or laterally, as and for the purpose specified.
3. In a fire-escape, the combination, with the 50 bell and vibrating frame, of a vertically-sliding horizontal bar attached to the latter, a hammer-head which slides on said bar, and screws for clamping the parts in any required adjustment, as shown and described.
4. In a fire-escape, the combination of the 55 bell and its supporting-standard having a lengthwise slot with the hammer proper, made adjustable, as specified.
5. In a fire-escape, the combination, with the 60 escape-wheel, constructed with teeth like an ordinary spur-gear, of the lever or anchor having rounded ends and flat inner faces which are transverse to the axis of the lever, the rotary gearing, and traveling ladder, all as shown and described, to operate as specified. 65
6. An escapement lever or anchor having hinged faces and springs pressing on the latter, as and for the purpose specified.
7. An escapement lever or anchor having rounded ends and hinged spring-pressed 70 pieces constituting their inner faces, as shown and described.

DAVID H. DILLMAN.
